Primary Examiner — T. Chase Nelson*Assistant Examiner* — Mark Cavanna(57) **CLAIM**

The ornamental design for a neurostimulator assembly, as shown and described.

DESCRIPTION

FIG. 1 is a perspective view of a neurostimulator assembly showing our new design;

FIG. 2 is a top plan view thereof.

FIG. 3 is a bottom plan view thereof.

FIG. 4 is a right side elevational view thereof.

FIG. 5 is a left side elevational view thereof; and,

FIG. 6 is a rear elevational view thereof.

With reference to FIGS. 1-6, the broken lines which define the bounds of the claimed design form no part thereof.

1 Claim, 5 Drawing Sheets Reduce screw (a) to broken line.
